COMBUSTION TURBINE

Alexander J. Jodelko, New York, N. Y.

Application April 27, 1932, Serial No. 607,840

6 Claims. (CL. 60—41)

The object of the invention is to provide a combustion turbine adapted to be operated by combustion gases formed by the ignition of fuel and air under relatively great pressure; to provide a turbine composed of two units selectively operable, so that the machine as a whole may be operated by one or the other to selectively secure rotation in either direction; to provide a turbine incorporating means for compressing air to secure the high temperature of the latter for ignition purposes; to provide a synchronized valve control for simultaneously introducing the air under pressure and a fuel charge into an ignition chamber and conducting the resultant explosive charge to the stator; to provide a machine incorporating means for the circulation of air in the rotor to keep the latter cool; to provide a construction in which the exhausted fuel charge is withdrawn after it has done its work; to provide a manual control for the synchronized valves to selectively vary the time interval of their operation or render them inert in closed position; and generally to provide a turbine which, for carrying out all of the functions for which it is designed, is of comparatively simple form and susceptible of cheap manufacture.

With this object in view, the invention consists in a construction and combination of parts of which a preferred embodiment is illustrated in the accompanying drawings but to which the invention is not to be restricted. Continued use in practice may dictate certain changes or alterations and the right is claimed to make any falling within the scope of the appended claims.

35 In the drawings:

Figure 1 is a top plan view of a turbine constructed in accordance with the invention, the fuel supply means being omitted. The conduits 69 are not shown in Figures 1 and 3. To do so would only confuse the general showing.

Figure 2 is a sectional view on the plane indicated by the line 2—2 of Figure 1.

Figure 3 is a plan view, on an enlarged scale, of the intermediate portion of the machine.

45 Figure 4 is a sectional view on the plane indicated by the line 4—4 of Figure 3.

Figure 5 is a sectional view on the plane indicated by the line 5—5 of Figure 1.

Figure 6 is an enlarged diametrical horizontal 50 sectional view of one of the turbine units of the machine.

Constructed on the turbine principle but designed to run in either direction, the invention comprises two turbine units A and B disposed at the remote ends of a base C, in axial alignment,

so that they may be coupled to a common shaft 10, mounted in appropriate bearings in pillar blocks 11 either cast integral with or formed separately from but attached to the base C. The two turbines A and B are designed to be supplied separately and are accordingly constructed to run in opposite directions when energized, the unenergized unit being driven by the energized unit in the operation of the machine.

The principle of operation is based on the principle of igniting the fuel by subjecting it to air under pressure, for example, thirty atmospheres, so that the intense heat acquired by the air under compression will serve to ignite the fuel. To this end an ignition apparatus D is provided, as are also the air compressors F and the fuel pumps G, the fuel pumps and the air compressors being in pairs with the units of each pair disposed on opposite sides of the shaft 10 and operatively connected with the latter. The exhaust gases are removed from the turbines by the scavenging pumps H, also consisting of a pair of units disposed one on each side of the shaft 10 but operatively connected therewith.

Except for being constructed to rotate in opposite directions when energized, the two turbine units are identical and each comprises a stator composed of a sectional housing 12 having the two sections joined on a horizontal diametrical plane, as by fasteners passed through the flanges 14. The stators also include the stationary blades 15 enclosed by the housing and of progressively increasing diameter from the intake to the discharge end, the discharge ends of the two turbines being directed toward each other and therefore toward the apparatus mounted at intermediate points on the base C. The rotors of the stators comprise the cores 16, the hollow shaft 17 on which the cores are mounted, and the blades 18 which are disposed in cooperative relation with the stator blades 15 and are of progressively increasing diameter, so that as the swiftly moving gases pass between the blades of the stator and rotor, rotation may be imparted to the latter.

The shafts 17 each comprises two shaft sections 17^a, each section constituting a journal mounted in an appropriate bearing 19 carried by the housing. The shaft 17 does not, however, extend through the rotor core 18 but the two sections are coupled to the core, being formed at their ends within the housing proper with cap plates 20 connected together by axial bolts 21, these bolts serving to secure the shaft sections to the core and likewise to hold the rotor blades in position on

the latter. A back pressure plate 21^a is secured to the cap plate at the intake end of the rotor and between this and the rotor blades, and at the exhaust end of the rotor, are secured the heat shields 21^b, these shields being made preferably of a tungsten-steel alloy and covering the heads of the bolts 21 to preserve them against the deleterious effects of the heated gases.

The bore of the rotor shaft extends through the two sections and constitutes an air intake to be utilized for cooling purposes and to make this conduit continuous from the outer end of the shaft, the core is formed axially with a cross-sectionally annular opening 22 of progressively increasing diameter and having on its interior peripheral surface spirally arranged blades 23. Fans 24 are disposed between the clamp plates 20 and the core but rotate with the latter, so that when the rotor is in motion, air passes through the hollow shaft section at the outer end of the latter, being drawn in by the fan 24 adjacent that end, and is then passed through the annular opening in the core to the next fan 24 and then out through the inner shaft section 17^a which, at its point of coupling with the shaft 10, is provided with radial outlets 24' formed in the hub of a fan 25 disposed in the housing 26 mounted on the base C. The air thus entering the fan housing 26 through the openings 24' of the hub of the fan 25, is discharged from the housing through peripheral outlets communicating with conduits 30 from which it is discharged, either to the atmosphere or to the inactive or unenergized turbine unit, as hereinafter appears.

35 The combustion gases by which rotation of the rotor is effected pass from the ignition apparatus D through the conduits or feed tubes 31 and are delivered by the latter to the stator interiorly, as indicated by the gas intake chambers 32. The swiftly moving gases then pass between the blades of the stator and rotor, imparting movement to the latter, and enter the exhaust chamber 33, from which they are discharged through the exhaust conduits 34 which are in communication with the intake of the exhaust pumps H.

As above indicated, the shafts 17 of the two turbine units A and B are coupled to the shaft 10, so that when either one or the other is in motion, the shaft 10 is rotated and therefore the pump units G, F, and H and ignition apparatus D are set in motion, these having operative connections with the shaft 10, by reason of the countershafts 35 which are disposed on diametrically opposite sides of the shaft 10 but parallel with the latter and rotatably mounted in pillar blocks 36. Motion is communicated to both countershafts 35 through the instrumentality of pinions 37 carried by the shaft 10 and meshing with gears 38 mounted on the countershafts at opposite ends of the latter.

The exhaust or scavenging pumps H are preferably mounted at an intermediate point in the length of the base C, so that they are disposed at a midpoint between the two turbine units A and B. The cylinders of the pumps H are covered at the upper ends with housing or cap members 39 having discharge outlets 40. Webs 41 constitute the top walls or heads of the cylinders of the pumps and these webs are formed with openings normally closed by spring-seated valves 42, the valves opening outwardly—that is, away from the pistons 43. Thus, on an upward stroke of the piston, the valves 42 will open and discharge from the cylinder the exhaust gases contained therein.

75 The piston itself is likewise formed with a plu-

rality of ports normally closed by spring-seated valves 44, these opening upwardly, toward the web plate, so that they may be held in closed position during the ejection stroke but open on the downward or intake stroke. Positioned in the cylinder immediately below the piston in the lowermost position of the latter is a web plate 45. This web plate is likewise provided with ports and these are normally closed by spring-seated valves 46 opening upwardly or toward the piston, so that in the ascending movement of the piston the valves will be opened and closed on the descending movement. The piston is closed at its lower end with a head 47 and just above the latter is provided with lateral intake ports 48 by means of which communication between the cylinder and the exhaust conduits 34 is had by means of nipple connections 49. Thus, any exhaust gases in the exhaust conduits will, on the upward stroke of the piston, be drawn in through the ports 48 and through the valve controlled openings in the web plate 45, behind the piston. As the latter descends, these gases will be transferred to the upper side of the piston and be ejected through the valve controlled openings in the web plate 41 and through the exhaust outlet 40 to the atmosphere.

The pistons of the pumps H are actuated from the crank shafts 35 by reason of the cranks 50 formed in the latter and the connecting rods 51 between the piston rod and the cranks 50.

Intermediate pillar blocks 36^a are mounted on the base C and between these and on the countershaft 35 are positioned oil circulating pumps 52 by means of which oil is circulated to the various bearings and other parts requiring lubrication.

The air compressors F are positioned next adjacent the scavenging pumps H and these consist each of a cylinder in which a piston 53 moves, the reciprocatory movement of the piston being derived from the countershaft 35 by reason of a connecting rod 54 which is connected with a crank 55 in the countershaft. Upwardly opening spring-seated valves 56 normally close ports formed in the piston, and on the downward stroke of the latter the valves will be open but on the upward stroke will be closed, so that the air above the piston will be driven through the valve closed openings in the head of the latter, said head being provided with ports normally closed by spring-actuated valves 57, these valves 57, however, opening upwardly, so that opening movement is accomplished on the upward stroke of the piston, whereas they will remain closed on the downward stroke. The head of the cylinder 58 is covered with a housing 58 and the two pump units F are interconnected by means of a header 59 which places the two pump units in communication through ports or openings 60 formed laterally in the housings 58. As the two countershafts rotate, the pistons 53 of the two pump units are reciprocated, the downward stroke serving to fill the cylinders with air by reason of the valves 56 opening and the upward stroke serving to eject the air into the housings 58 from which it passes to the ignition apparatus for utilization as hereinafter appears.

Disposed immediately beside the air compressor units F are the fuel pumping units G. These are likewise disposed one on each side of the center or power shaft 10 and are each actuated by one of the countershafts 35. The cylinder of the fuel pump is immediately next to the cylinder of the air compressor and its head is ported with the ports normally closed by spring-seated up-

wardly opening valves 61. The piston 62 is likewise ported, with the ports normally closed by upwardly opening spring-seated valves 63. The reciprocatory motion of the piston is derived from 5 the countershaft 35 by reason of the crank 64 on the latter and the connecting rod 65 by which an operative connection is effected between the piston and the countershaft. The cylinder of the fuel pump is covered at the head with a housing 66 and the two fuel pump units are interconnected by means of a header 67 by means of which communication between the two housings is effected by lateral ports 68 in the housings.

The fuel supply comes from a supply source 15 through the conduit 69 from which it passes through a supply tube 70 and strainer 70a into a compartmental chamber 71, the compartments of which are defined by a division wall 72 formed with nozzles 73. Communication between the 20 supply tube 70 and the upper compartment of the chamber is controlled by a needle valve 74, and the fuel reaching this compartment passes through the nozzles 73 into the lower compartment from which it passes into the conduits 75 leading to chambers 76 disposed directly above the cylinders of the fuel pumps. The conduits 75 serve as a supporting means for the chamber 71 as well as a means for effecting communication between it and the chambers 76 and the 25 latter are supported above the fuel pump cylinders by fuel tubes 77, which communicate with the cylinders, as indicated at 78, just below the plane of the valves 61. One of the fuel tubes 77 is equipped with a petcock 77a for the purpose 30 of examining the character of fuel being delivered. The fuel tubes, aside from acting as supports for the chambers 76, also serve as a means for communication between these chambers and the pump cylinders. The fuel tubes communicate 35 with the chambers 76 above the plane of the valve 78, the opening movement of which is controlled by adjustable stop pins 79 mounted in the top walls of the chamber 76. The valves 78 control openings in partition members 80 which 40 divide the chambers 76 into two compartments, with the lower of which the conduits 75 communicate and with the upper of which the fuel tubes 77 communicate. On the downward stroke of the piston 62, air below the latter which has 45 entered through lateral ports 81 formed in the cylinder walls passes the valve controlled openings in the piston by reason of the valves 63 being unseated by such air pressure. At the same time, sufficient suction is created in the 50 fuel tube 77 to draw fuel into the cylinder which is mixed with the air and on the upward stroke of the piston 62 this is ejected into the chambers formed by the housing 66 by reason of the valves 81 then opening. The fuel then passes into the 55 head 67 and thence to the ignition apparatus. The fuel which drops from the upper compartment of the chamber through the nozzles 73 enters the lower compartments of the chambers 76 and partly by reason of the suction in the fuel 60 tube 77 and partly by the rising head of fuel in the chamber 71, reaches the upper compartment of the chamber 76 for passage into the fuel pump cylinders.

A valve controlled drain 82 is mounted in the 65 lower wall of the chamber 72 for clean out purposes.

The fuel taken in by the fuel pumps G and the air compressed by the air compressors F are delivered to the ignition apparatus D, the former 70 through conductor tubes 83 in communication

with the header 67 and the latter through conductor tubes 84 in communication with the header 59.

The ignition apparatus D comprises a compartmental case or chest disposed one each on 5 diametrically opposite sides of the main shaft 10, with the compartments thereof controlled by means of valves actuated from the countershafts 35. Each compartmental chest or housing 85 is divided by means of a horizontal partition and 10 upright partitions so as to provide compartments 86, 87 and 88. There are preferably three or more of the compartments 88 and an equal number of each of the compartments 86 and 87, the two latter being of a combined width equal to the 15 width of the former. The conductor tubes 83 place the header 67 in communication with the compartments 86, while the conductor tubes 84 place the compartments 87 in communication with the header 59. Thus, the fuel drawn in by 20 the fuel pumps is transferred to the compartments 86 and the air compressed by the compressors transferred to the compartments 87. In each pair of compartments 86 and 87, the fuel in the one is introduced to the compressed air in 25 the other by the two being admitted simultaneously into the compartment 88 directly below and to this end the horizontal partition defining the bottom wall of the compartments 86 and 87 is formed with ports closed by means of the valves 30 89 and 90 which are operatively connected for actuation in unison by being connected with a common stem 91. When the set of valves 89-90 is opened, the fuel is ignited by contact with the highly heated air, this ignition taking place in 35 the compartment 88 and the high velocity of the gases resulting from the ignition is translated into turning movement of the rotor, reaching the latter through the conduit 31. Since in the illustrated embodiment of the invention, the ignition 40 apparatus comprises three sets of compartments on a side, all of the chambers or compartments 88 on the one side are connected to the intake end of one stator through a corresponding number of tubes 31, the corresponding number of chambers 88 on the other side of the power shaft being connected to the opposite stator in a similar manner. The compartments 86 and 87 of the ignition apparatus are connected by cross conductors 86a and 87a, these being for the purpose 45 of equalization.

The means for actuating the valve sets 89-90 comprises cylinders 92 which are peripherally toothed throughout their length. In each one of these cylinders, at the upper end, is threaded 50 the lower end of a valve stem 91, as indicated at 93. This provides for axial adjustment of the cylinder with reference to the valve stem, so that the extent, as well as the interval of time during which the valve is open may be determined 55 by reason of the fact that valve opening movement is communicated to the stem from the cylinder and to the latter from an abutment collar 93' on a push rod 94 having a pivotal connection with the eccentric strap 95 of the eccentric 96 60 65 which is mounted upon and driven by the countershaft 35. The rotation of the countershaft 35 will obviously impart reciprocatory movement to the push rod 94, so that the abutment collar will engage the cylinder and thereby lift or unseat the 65 valve set 89-90. Springs 97 are compressed between the abutment collars 93' and a guide bracket 98 in which the push rods 94 are slidably mounted. These springs prevent rattle in the reciprocatory movement of the push rods. Sim- 70 75

ilarly, springs 99 are compressed between collars 100 mounted on the valve stem and a valve stem guide 101. The springs 99 thus serve to yieldingly hold the valves 89—90 in closed position and against the pressure of which they are opened by reason of the collars 93' abutting the lower ends of the cylinders 92 when the push rods are elevated by the eccentric.

The threaded connection between the cylinders 10 and the valve stem provides, as above stated, for axial adjustment of the cylinders on the valve stem, so that their effective length may be varied by reducing or increasing it, so that thereby the length of time that the collars 93' engage the cylinders is determined by their adjustment on the valve stems 91. If the cylinders be elevated to the point where the abutment collars will not engage them in the highest position of the push rods 94, the operation of the valves will be stopped 20 which will stop the turbine units by reason of the fuel and air supply being then cut off.

It is essential that the adjustment of the cylinders 92 be effected with timed relation to each other or synchronously and that the adjustment 25 be possible from some exterior source. Therefore, between each pair of adjustment cylinders 92 there is positioned a rotary drum 102, formed at an intermediate point in its length with the spur teeth 103 which mesh with the teeth formed 30 on the peripheries of the cylinders 92. Rotary or turning movement being imparted to these drums 102, the cylinders 92 will obviously be rotated and thereby adjusted axially of the valve stems 91. To provide for the simultaneous or 35 synchronous rotation of the drums 102 they are formed at their lower ends with worm wheels 102a by means of which a worm connection is effected with the shaft 105 on which is mounted a spur gear 106 which is the terminal unit of a gear train 107 of which the initial unit is driven by a bevel gear 108 in mesh with a bevel pinion 109 on a vertically disposed shaft 110 carrying at its lower end a worm gear 111 in mesh with a worm 112 actuated by a shaft 113 to which motion 40 is manually communicated by means of a hand wheel 114.

The valve adjustments of oppositely disposed ignition apparatus are simultaneously effected by the apparatus above described, but when the 50 valves are adjusted for full opening movement on the one side, those on the other side are adjusted to remain inactive. In other words, when the cylinders of the valves of one ignition apparatus are adjusted to open fully, the cylinders on the opposite apparatus are so adjusted that they will be unresponsive to reciprocatory movement of the abutment collars or washers 93 and their respective push rods 94. Thus it will be seen that either one or the other of the turbine units is energized 55 by the adjustment of the valves in the ignition apparatus and since the units are constructed to run in relatively opposite directions, either direction of rotation of the complete apparatus is secured by the adjustment of the valves and this 60 by the operation of the hand wheel 114 in one direction or the other, to impart the necessary movement to the gear mechanism by which the adjustment of the cylinders 92 is effected. Also, the adjustment of the cylinders on the valve stem may be effected so that none of them may 65 be engaged by the abutment collars 39'. When the hand wheel 114 is rotated, the cylinders 92 of one set of valves are elevated and the other set lowered, since in any direction of rotation of the 70 hand wheels, the cylinders of the two sets are re-

spectively rotated in opposite directions. The cylinders of that set which are lowered are moved toward the abutment collars, while the cylinders of the opposite set are moved away from the abutment collars. The set being moved toward the abutment collars is the set which will be engaged by the abutment collars and is the set whose valves will be operated when the cylinders reach the range of movement of the abutment collars. Thus, there is determined the turbine unit which 10 will be operated. When the cylinders in the two sets, however, lie in the same horizontal plane, neither set is within the range of movement of the abutment collars and therefore the valves of neither unit of the ignition apparatus may be operated. Such an adjustment of the cylinders is the one which is effected to bring the apparatus to rest and that is the setting of the cylinders that will obtain during the starting operation.

The air discharged into the conduit 30 by the 20 fans may, by reason of the peculiar construction, be employed to cool the exhaust conduit 34, since each of these adjacent its point of connection with the exhaust pump is provided with a pipe coil 115 interiorly thereof. One end of this pipe coil 115 25 is connected with the pipe 116 which is tapped into the conduit 30 but is provided with a valve 117 at this point. The conduits 30 of the opposite turbine units are connected together with a valve 118 interposed and this valve is shunted with a pipe 30 119 provided with valves 120 and a valve 121. The air thus delivered by the fan may be exhausted to the atmosphere by closing the valve 117 and opening a valve 120 nearest the fan delivering the air and also opening the valve 121. Thus the air passes from the fan through the conduit 30 and into the shunt pipe 119 and thence out through the valve 121. Desiring to use the air to cool the exhaust conduit 34 nearest the fan delivering the air, the valve 120 is closed and 40 the valve 117 opened when the air will pass from the conduit 30 into the pipe 116 and then through the coil 115 and out to the atmosphere. Similarly, the air delivered by the fan may be driven through the coil 115 of the exhaust tube 34 of 45 the conduit operating and simultaneously through the coil in the exhaust tube of the opposite unit, by opening both valves 120 and both valves 117 but closing valve 121. Then the air in the conduit 30 passes into both pipes 116 and around both 50 coils 115 to the atmosphere. Instead, the air of the fan of the turbine under operation may be driven direct through the conduit 30 to the opposite fan and out through the hollow shaft of the opposite turbine unit by closing the valves 117 55 and 120 and opening valve 118. To provide for the exhaust pump taking in the exhaust charges where they are subjected to the cooling effect of both coils 115, the conduits or exhaust tubes 34 are interconnected by a tubular connection 122 60 containing a valve 123. Thus, if this valve 123 is opened and the air in the conduit 30 permitted to circulate in both coils 115, there will be an increased cooling effect and the intake on the exhaust pump will be in the region of both of these 65 cooling zones.

The cylinders of the exhaust pumps are connected by means of an equalizing header 124 which exhausts to the atmosphere.

The invention having been described, what is 70 claimed as new and useful is:

1. A combustion turbine comprising a pair of stators, a pair of rotors of which one is rotatably mounted in each stator, a shaft common to said rotors, the two rotor-stator pairs being rel- 75

atively reversed in position so that the shaft may be rotated in either direction depending on which pair is energized, a fuel charge compressor in communication with a source of fuel supply, an air compressor, a pair of compartmental elements respectively having fuel chambers, air pressure chambers and combustion chambers of which the combustion chambers of said compartmental elements are respectively in communication one with each of the stators exteriorly of the rotor thereof, the fuel charge compressor being in communication with the fuel chambers, the air compressor being in communication with the air pressure chambers, the fuel and air pressure chambers of said compartmental element being respectively in communication with its cooperating combustion chamber, valves controlling communication between the fuel chambers and said combustion chambers and between the air pressure chambers and said combustion chambers, operative connections between the rotors and said valves, and manual means for adjusting all of said valves including operative connections between the valves of both compartmental elements, whereby adjustment may render the valves of either compartmental element active and the other inactive to direct the fuel charges ignited to one or the other of the stators.

2. A combustion turbine comprising a base, a stator mounted at opposite ends of the base, a rotor rotatably mounted in each stator, the two rotors rotating in respectively opposite directions when energized, a centrally disposed shaft common to the two rotors, fuel charge compressors mounted respectively on opposite sides of said shaft and between said stators and operatively connected with said shaft for rotation by the latter, said fuel compressor being in communication with a source of fuel supply, a pair of air compressors disposed between said stators and on opposite sides of said shaft and operatively connected with the latter, a pair of compartmental members mounted respectively on opposite sides of said shaft with the compartments of each constituting respectively combustion, air pressure chambers and fuel chambers, the fuel charge compressors having their discharges in communication with the fuel chambers, the air compressors having their discharges in communication with the air pressure chambers, the combustion chamber of one compartmental unit being in communication with one stator exteriorly of the rotor thereof and the combustion chamber of the other compartmental unit correspondingly communicating with the other stator, valves controlling communication between the fuel chambers and combustion chambers of each compartmental unit, valves controlling communication between the air pressure chambers and combustion chambers of each compartmental unit, the fuel chambers and the air pressure chambers of the two compartmental units being in communication with each other, operative connections between said shaft and said valves for synchronously operating the valves of the fuel chambers and air pressure chambers in unison, and adjustable means included in said operative connections for selectively rendering the valves of either compartmental unit active and the other inactive, whereby the combustion chambers of either compartmental unit may be rendered active and its connected rotor correspondingly rendered responsive thereto.

3. A combustion turbine comprising a pair of stators, a pair of rotors of which one is rotat-

ably mounted in each stator, a rotor shaft common to said rotors, the two rotor-stator pairs being relatively reversed in position, so that the shaft may be rotated in either direction, depending on which pair is energized, a fuel charge compressor in communication with a source of fuel supply, an air compressor, a pair of compartmental elements respectively having fuel chambers, air pressure chambers and combustion chambers of which the combustion chambers of said elements are respectively in communication one with each of the stators exteriorly of the rotors thereof, the fuel charge compressor being in communication with the fuel chambers, the air compressor being in communication with the air pressure chambers, the fuel and air pressure chambers of said compartmental elements being respectively in communication with its cooperating combustion chamber, valves controlling communication between the fuel chambers and said combustion chambers and between the air pressure chambers and the combustion chambers, operative connections between the rotors and said valves to effect opening movement of the latter on the rotation of the rotors, and a transverse shaft positioned intermediately between the stators for adjusting all of said valves and provided with a hand wheel and with operative connections with the valves of both compartmental elements whereby the valves controlling communication to one stator may be held inactive while the valves controlling communication to the other stator may have their time period of opening movement varied.

4. A combustion turbine comprising a pair of stators, a pair of rotors of which one is rotatably mounted in each stator, a rotor shaft common to said rotors, the two rotor-stator pairs being relatively reversed in position, so that the shaft may be rotated in either direction depending on which pair is energized, a fuel charge compressor in communication with a source of fuel supply, an air compressor, a pair of compartmental elements respectively having fuel chambers, air pressure chambers and combustion chambers of which the combustion chambers of said elements are respectively in communication one with each of the stators exteriorly of the rotors thereof, the fuel charge compressor being in communication with the fuel chambers, the air compressor being in communication with the air pressure chambers, the fuel and air pressure chambers of said compartmental elements being respectively in communication with its cooperating combustion chamber, valves controlling communication between the fuel chambers and said combustion chambers and between the air pressure chambers and the combustion chambers, operative connections between the rotors and said valves to impart opening movement to the latter on rotation of the rotors, axially adjustable members included in said operative connections, a gear train operatively connecting said axially adjustable members of each compartmental element, and a transverse shaft operatively connected with both gear trains, whereby the axially adjustable elements of the two compartmental elements may be simultaneously adjusted in opposite directions to successively vary the degree of opening movement of the valves controlling communication with one stator while leaving the valves of the other stator inactive and vice versa.

5. A combustion turbine comprising a pair of stators, a pair of rotors of which one is rotatably mounted in each stator, a rotor shaft common

- to said rotors, the two rotor-stator pairs being relatively reversed in position, so that the shaft may be rotated in either direction depending on which pair is energized, a fuel charge compressor in communication with a source of fuel supply, an air compressor, a pair of compartmental elements respectively having fuel chambers, air pressure chambers and combustion chambers of which the combustion chambers of said elements are respectively in communication one with each of the stators exteriorly of the rotors thereof, the fuel charge compressor being in communication with the fuel chambers, the air compressor being in communication with the air pressure chambers, the fuel and air pressure chambers of said compartmental elements being respectively in communication with its cooperating combustion chamber, valves controlling communication between the fuel chambers and said combustion chambers and between the air pressure chambers and the combustion chambers, the fuel chambers and the air pressure chambers being grouped in pairs of which each comprises a fuel chamber and an air compression chamber, the valves of each pair having a common stem, reciprocating abutment members for each valve stem operatively connected with said shaft, a cylinder threaded on each valve stem for axial adjustment along the latter, an abutment collar carried on each reciprocating member for engagement with the end of its attendant cylinder to effect unseating movement of said valves, geared connections between the cylinders of the valves controlling communication with each stator, shafts operatively connected with said connections, a gear train operatively connecting said shafts, and means for manually rotating one of the elements of said gear train to rotate said shaft in one direction to adjust the degree of opening movement of the valves of one rotor without affecting the valves of the other, or to rotate the shafts in the opposite direction to similarly but reversely affect the two sets of valves.
6. A combustion turbine comprising a pair of stators, a pair of rotors of which one is rotatably mounted in each stator, a rotor shaft common to said rotors, the two rotor-stator pairs being relatively reversed in position, so that the shaft may be rotated in either direction depending on which pair is energized, a fuel charge compressor in communication with a source of fuel supply, an air compressor, a pair of compartmental elements respectively having fuel chambers, air pressure chambers and combustion chambers of which the combustion chambers of said elements are respectively in communication one with each of the stators exteriorly of the rotors thereof, the fuel charge compressor being in communication with the fuel chambers, the air compressor being in communication with the air pressure chambers, the fuel and air pressure chambers of said compartmental elements being respectively in communication with its cooperating combustion chamber, valves controlling communication between the fuel chambers and said combustion chambers and between the air pressure chambers and the combustion chambers, the fuel chambers and the air pressure chambers being grouped in pairs of which each comprises a fuel chamber and an air compression chamber, the valves of each pair having a common stem, reciprocating abutment members for each valve stem operatively connected with said shaft, a cylinder threaded on each valve stem for axial adjustment along the latter, an abutment collar carried on each reciprocating member for engagement with the end of its attendant cylinder to effect unseating movement of said valves, geared connections between the cylinders of the valves controlling communication with each stator, shafts operatively connected with said geared connections, a gear train operatively connecting said shafts, and means for manually rotating one of the elements of said gear train to rotate said shafts in one direction to adjust the degree of opening movement of the valves of one rotor without affecting the valves of the other, or to rotate the shafts in the opposite direction to similarly but reversely affect the two sets of valves, the gear train unit actuating means comprising a hand wheel and a connected shaft extending transversely to the rotor shaft but operatively connected with said gear train unit.

ALEXANDER J. JODEIKO.
